UNITED STATES PATENT OFFICE.

OLIVER J. MOUSSETTE, OF RICHMOND HILL, NEW YORK.

CRUSHER.

Application filed October 7, 1920. Serial No. 415,284.

To all whom it may concern:

Be it known that I, OLIVER J. MOUSSETTE, a citizen of the United States, residing at Richmond Hill, in the county of Queens and 5 State of New York, have invented a certain new and useful Crusher, of which the following is a specification.

This invention is a crusher intended more particularly for the crushing of minerals, 10 ores, stones, slag and analogous materials. The machine is so constructed that the crushing of the ores or the like may be carried on to a point wherein the mineral is pulverized, although, in practice, the crushing 15 operation may be carried to any degree of fineness desired.

The object of the invention is to provide a strong, compact and efficient construction, which will last well under constant use and 20 will not be apt to get out of order.

A further object of the invention is to so constitute the machine that the crushing action will be rapid and of such efficiency that the passage of material therethrough 25 may be accomplished in minimum time, so as to bring the output of the machine to a maximum.

In the preferred practical manner of carrying out the present invention, the same 30 embodies a cylindrical shell provided with suitable lining which is preferably toothed or serrated circumferentially. This cylindrical shell is rotated by any suitable means and within the same operates a plurality of 35 gravity actuated crusher rolls which may be coordinated to operate together or independently and are shaped, in the main, substantially complementarily to the toothed or serrated lining of the shell, whereby the 40 material within the shell is operated upon simultaneously by the shell lining and the crusher rolls broken into smaller and smaller pieces depending upon the duration of the operation.

45 Features of the invention, other than those adverted to, will be apparent from the hereinafter detailed description and claims, read in conjunction with the accompanying drawings.

50 The accompanying drawings illustrate different practical embodiments of the present invention, but the constructions therein shown are to be understood as illustrative, only, and not as defining the limits of the 55 invention.

Figure 1 is a central longitudinal section through a machine embodying the present invention.

Figure 2 is an elevation of the machine as viewed from the discharge end thereof. 60

Figure 3 is a face view of an end plate which is employed to close the feed end of the cylindrical shell.

Figure 3^a is a section on the curved line 65 3^a—3^a of Figure 3.

Figure 4 is a similar view of the end plate at the discharge end of the shell; and

Figures 5 and 6 are detail views of a modified form of crusher roll which may be employed. 70

In the form of the machine shown in the drawings, the cylindrical shell is supported for rotation upon a stationary base embodying two end frames 1, spaced apart by side frames 2 rigidly secured to the end frames and forming therewith a firm and rigid base. The end frames are provided adjacent each side thereof with bearings 3 and 4, the bearings 3 serving to support a shaft 5 for rotation, and the bearings 4 75 serving as a support for a parallel shaft 6. The shaft 5 projects beyond the bearing 3 of one of the end frames 1 and carries fast and loose pulleys 7 and 8 about which a belt 80 from any suitable prime mover may be passed.

Moreover, the shafts 5 and 6 are geared together for simultaneous rotation by means of a sprocket chain 9, which is passed over a sprocket 10 fixed on the shaft 5 and over 85 a sprocket 11 fixed on the shaft 6.

On the shafts 5 and 6 and adjacent the bearings 3 and 4 are fixed flange rollers 12 on which are adapted to ride carrier rings 13, which support the cylindrical shell 14 90 interiorly of which the grinding takes place. The construction is such that when the drive belt cooperates with the fixed pulley 7, the shafts 5 and 6 are operated and through the supporting rollers 12 serve to 95 rotate the carrier rings 13 to the end that the cylindrical shell 14 may be rotated.

While the shell 14 may partake of various forms, and be constructed in different ways, depending upon the work it is intended to perform, it is found advantageous to construct said shell from a plurality of sections 14', each of which is annular in form and is provided with suitable flanges, whereby a plurality of said sections may be riv- 105 110

eted or bolted together to build up the cylindrical shell desired. The shell thus formed is mounted within the carrier rings 13 and supported and carried thereon.

5 The shell 14 is preferably provided with suitable lining, which may be constructed from metal or stone, but is preferably of the former. This lining may be furthermore formed in sections 15' corresponding 10 to the sections 14' of the shell, thereby not only minimizing the work of transportation of the parts prior to assembling or after dismantling, but further enabling worn or broken sections to be removed and replaced 15 without necessitating the provision of an entire new lining in the event of breakage at any particular point. While this structure is recommended, however, the lining may, if desired, be formed otherwise and in sections 20 or if preferred the cutting configuration hereinafter referred to on the interior of the lining may be formed on the interior of the shell sections 14' and the lining entirely omitted.

25 The inner face of each section of the lining is formed into circumferential teeth or serrations 15, so as to provide cutting or cracking edges interiorly of the shell to the end that the crushing operation may be 30 more efficiently carried out. The inner face of the lining may further be formed to embody a helical screw configuration throughout its entire extent by cutting a helical thread 16 into circumferentially disposed 35 teeth 15. This helical thread serves to feed the material operated upon longitudinally through the shell and while such thread may extend from end to end of the lining, it is found, in practice, that very good feeding 40 results may be accomplished by forming the helical thread 16 in only the end sections of the lining, as shown in Figure 1 of the drawings, so that material introduced into the left hand end of the machine as shown in 45 Figure 1, will be separated on its way through the shell and finally fed out of the shell by the cylindrical shell at the right hand or discharge end of the machine.

Positioned within the shell 14 and 50 adapted for operation therein is a crushing member 17, which, in the form of the invention shown in Figure 1, embodies a plurality of crushing elements 17', each of which is in the form of a beveled edge roll. 55 All of the rolls are of the same diameter less than the interior diameter of the lining of the shell and are bolted together for simultaneous operation by a bolt 18. Excessive strain is taken off of the bolt by forming a 60 boss on each roll adapted to fit into the adjacent face of the adjacent roll as shown in Figure 1, so that when the rolls are bolted together, the crushing element thus formed acts as a unitary structure.

65 The rolls 17' are, moreover, individually

beveled as shown to correspond with the serrations on the interior of the lining so that the interior of the lining and the operative surface of the crushing member is complementarily shaped, for the purpose of effecting 70 crushing relation of maximum efficiency. The crushing member is unattached with respect to the cylindrical shell and simply rests idly therein, so that when the shell is rotated, the crushing element revolves within 75 the shell and is constantly under the influence of gravity which draws it to the lowest point therein.

The feed end of the shell is closed by an end plate 19 perforated at 119 and provided with a feed opening 19' to which the material is fed through a feed hopper 20. The feed opening 19' is positioned at the beginning of the helical feed groove or thread 16. The other, or discharge end, of the 85 machine is closed by a discharge end plate 21, having an outlet opening 21' communicating with a discharge hopper 22. Directly adjacent the inner face of the end plate 21, but slightly spaced therefrom is a 90 second plate 23, which is perforated at 24 and has a main discharge opening 25, the latter of which is at all times in registration with the outlet 21' of the under plate.

The end plate 19 at the feed end of the 95 machine is provided on its outer face with a scoop shape baffle 19^b positioned so as to overlie one end of the feed opening 19', as shown best in Figures 3 and 3^a, so that as the shell is rotated, the scoop shape baffle 100 19^b directs material, introduced into the hopper, through the feed opening 19' in the end plate 19 into the interior of the shell. To facilitate this feed of material, the opposite ends of the feed opening 19' are cut on 105 a slant as shown at 19^a.

The material fed into the shell is caused to travel longitudinally thereof by the helical thread 16 and after traveling the entire length of the shell, passes out of the same 110 through the registering outlet openings 25 and 21' into the discharge hopper 22. During the passage of material through the shell, the shell is constantly rotated and the crushing member 17, in traversing the inner 115 circumference thereof, rides over the material and carries out the crushing operation. This operation is assisted by the fact that the crushing member in passing over the material meets with such resistance that it 120 cannot roll freely and it is carried around through the rotation of the shell until its weight overcomes the resistance, whereupon it falls to the base of the shell, and there engages with the material therein with considerable force. This force is sufficient to break up the hardest minerals or ores and even reduces them to a pulverized state. During the continued operation of the machine, the crushing member is literally tum- 125 130

bled within the shell and by this action efficiently carries out the crushing operation.

The material after passing through the crusher may be delivered from the discharge 5 hopper 22 to any other suitable mechanism for its disposal or treatment, but for the purpose of illustration, I have shown one practical method of disposing of such material.

In the showing made, the material upon 10 leaving the hopper 22 is adapted to pass by way of a sleeve 26 into a bin or box 29, provided at its lower end with a hinged door 29' through which the material may be removed from time to time. The hopper 15 22 is so shaped that its outlet end will at all times aline with the sleeve 26, during rotation of the shell, and said sleeve 26 is preferably supported for sliding movement in a longitudinal direction toward and away 20 from the end of the discharge hopper 22 in a sleeve 26' carried by a bracket 26^a and may be clamped in suitable adjustment by means of a set screw 26^b. Into the upper end of the bin 29 projects a pipe 27', the upper end of 25 which is associated with a blower 27 having an outlet pipe 28. During the operation of the machine, the blower is operated and, as soon as the bin 29 is closed produces a partial vacuum in this bin which sets up 30 suction in the sleeve 26. If the sleeve 26 is moved into relatively close proximity with the discharge end of the hopper 22, this suction will draw air from the interior of the shell 14, which air will be replaced by 35 air flowing into the shell through the perforations 119 at the feed end of the machine, thereby producing a constant circulation or draft of air through the shell to the blower. This draft of air will carry off dust and 40 other finely pulverized material contained in the shell and is rendered possible through the employment of the perforations 119 and 24 at the opposite ends of the shell. In practice, it is found that the amount of 45 draft or force of the air circulation may be readily controlled through the sliding of the sleeve 26 closer to or further away from the discharge end of the hopper 22, and by this move the current of air may be made 50 stronger or weaker so that finer or heavier particles can be drawn through by the blower 27 as may be desired.

In the event, it is desired to collect only 55 the finest dust through the blower, the sleeve will be moved further away from the end of the discharge hopper, whereas, for the collection of heavier particles, closer proximity between these parts would be had.

It is found that the material may be 60 graded in this way, although, in practice, the essential consideration is to remove the dust and other finely pulverized material expeditiously and efficiently. The material drawn through the blower is delivered 65 through the outlet pipe 28 for storage or

further treatment. In the event, the machine is being used as an ore pulverizer, the material delivered through the pipe 28 may be washed or otherwise treated to recover minerals therein.

It will be noted from the drawings that the apertures 24 in the perforated plate 25, as well as the corresponding apertures in the plate 19 are tapered in the direction of the air current, so that clogging of the machine through the wedging of lumps of material in these apertures could not occur. The expeditious removal of the dust and pulverized material is advantageous not only for the quick delivery of the same, but as the machine is kept free from finely divided or pulverized material, the crushing operation may be more efficiently carried out.

The forming of the interior of the shell in the manner hereinbefore described and shown in the drawings has many practical advantages. The serrations of both the crushing element and the lining of the shell not only produce relatively sharp edges for 85 grinding, but provide an uneven surface between the coacting crushing elements of the construction so that ore or other material may be more readily splintered into fragments during the operation of the machine. Furthermore, through the serration of the parts as described, the actual grinding surface is greatly enlarged over that of former machines of corresponding size, thereby imparting to the machine a high factor of 90 efficiency. This, in connection with the other advantages referred to, renders a relatively small machine, in practice, capable of delivering a relatively large output.

The machine hereinbefore described has 105 been found to operate with high efficiency on the material specified and others, but is capable of slight modification without departing from the spirit of the invention. For example, the crushing member 17, while shown in Figure 1 as embodying a plurality of rolls secured together to operate in unison, may, if desired, embody crusher rolls 17^a of the type shown in Figures 5 and 6 which differ from the rolls 17' merely in the fact 110 that they are not secured together by a bolt 18, but operate independently and are accordingly not formed with projecting bosses and boss receiving recesses. The machine of the present invention may embody a 115 crushing member of crushing rolls secured together as shown in Figure 1, or of independently operating separate rolls of the character shown in Figures 5 and 6.

Other details of construction than those 120 specified may be varied or equivalents employed without departing from the spirit or scope of the invention, which is to be understood as broadly novel as is commensurate with the appended claims.

Having thus fully described the invention, what I claim as new and desire to secure by Letters Patent is:

1. A crusher embodying a hollow cylindrical member mounted for rotation on a substantially horizontal axis, and gravity operated crushing means positioned interiorly of the cylindrical member, the interior face of the cylindrical member being substantially serrated in longitudinal cross section, and being provided adjacent at least one of its opposite ends with a helical channel cut through the circumferential serrations to facilitate the feeding of material through the cylindrical member.
2. A crusher embodying a hollow cylindrical member mounted for rotation on a substantially horizontal axis, the inner surface of said member being provided with annular ribs having helical grooves therein, and crushing means operable interiorly of said cylinder.
3. A crusher embodying a hollow cylindrical member mounted for rotation on a substantially horizontal axis, and a crushing element positioned for operation interiorly of said cylindrical member, the inner surface of the cylindrical member and the outer surface of the crushing element being striated circumferentially and also helically channelled longitudinally.
4. A crusher embodying a hollow cylindrical member mounted for rotation on a substantially horizontal axis, and a crushing element positioned for operation interiorly of said cylindrical member, the inner surface of the cylindrical member and the outer surface of the crushing element being striated circumferentially and the inner surface of the cylindrical member being further provided with a helical channel cut through said striations and adapted to feed material longitudinally of the cylindrical member while such material is being crushed between the inner surface of the cylindrical member and the outer surface of the crushing element.
5. A crusher embodying a cylindrical member provided on its interior with annular V-shaped ribs and having helical grooves cut through said ribs adjacent the inlet and outlet ends of said cylindrical member, and crushing means positioned for operation interiorly of said cylindrical member and embodying a plurality of crushing elements, each of which is provided with a tapered edge adapted, during the operation of the machine, to operate in a space between two adjacent ribs on the inner face of the cylindrical member, and means for securing all of the crushing elements together for simultaneous operation.
6. A crusher embodying a hollow cylindrical member mounted for rotation on a substantially horizontal axis, crushing means operable interiorly of the cylindrical mem-

ber; said cylindrical member having a helical channel formed on the inner surface thereof for facilitating the feed of material longitudinally of said member and means for introducing such material into one end of said member off center and substantially at the beginning of the helical channel.

7. A crusher embodying a cylindrical member mounted for rotation on a substantially horizontal axis, crushing means operable interiorly of said cylindrical member, end plates for closing the feed and delivery ends of the cylindrical member and a hopper positioned at the feed end of said member, in combination with a baffle plate carried by the feed end plate off center and on the exterior face thereof and projecting into the hopper and adapted to scoop material from the hopper and pass it through a charging opening in said feed end plate directly adjacent the baffle plate.

8. A crusher embodying a hollow cylindrical member mounted for rotation on a substantially horizontal axis and provided on its interior with annular V-shaped ribs, and a helical groove cut through said ribs adjacent the inlet end of said member, crushing means positioned interiorly of said member, an end plate positioned across the inlet end of said member and provided off center with an inlet opening directly adjacent one end of the helical groove, a hopper positioned beyond the inlet end of the cylindrical member, and a baffle plate rigidly mounted on the end plate adjacent the inlet opening, whereby the rotation of the cylindrical member causes the baffle plate to scoop material out of the hopper and pass it through the end plate and directly into the end of the helical groove.

9. A crusher embodying a substantially closed vessel provided with feed and discharge openings, means positioned within the vessel for crushing material introduced thereto, a settling chamber, suction means for producing a partial vacuum within the settling chamber, a pipe leading from the settling chamber into juxtaposition with the discharge opening of the vessel and mounted for longitudinal adjustment to vary the gap between the discharge opening of the vessel and the contiguous end of said pipe whereby the suction communicated to the interior of the vessel through the pipe may be governed by longitudinal adjustment of the pipe.

10. A crusher embodying a substantially closed chamber provided with inlet and discharge openings, means interiorly of the vessel for crushing material introduced therein, a settling chamber mounted in fixed position, suction means for producing a partial vacuum within the settling chamber, and a conduit leading from the settling chamber to a point adjacent the discharge

opening of the vessel and in alinement therewith, said conduit being mounted for adjustment to vary the gap between the discharge opening of the vessel and the contiguous end of said conduit whereby the strength of the suction communicated through the conduit to the exterior of the vessel may be regulated.

11. A crusher embodying a substantially closed vessel provided with an outlet, means inferiorly of the vessel for crushing material introduced therein, suction means, and

a conduit leading from the suction means into juxtaposition with the outlet of the vessel, said conduit being adjustable to vary the gap between the outlet of the vessel and the contiguous end of the conduit to vary the strength of the suction communicated through the conduit to the interior of the vessel.

In testimony whereof, I have signed my name to this specification.

OLIVER J. MOUSSETTE.
